UNITED STATES PATENT OFFICE.

EDWARD E. STEVENSON, OF LOS ANGELES, CALIFORNIA, ASSIGNOR TO D. & B. PUMP AND SUPPLY COMPANY, OF LOS ANGELES, CALIFORNIA, A CORPORATION OF CALIFORNIA.

PUMP-ROD-SUSPENSION DEVICE.

Application filed November 26, 1924. Serial No. 752,432.

This invention has to do with devices for suspending pump rods from walking beams, pump jacks and the like; the device connecting the upper end of the polish rod to the 5 free end of the beam or jack to transmit reciprocatory movement of the beam to the pump plunger carried by the line of sucker rods which extend from plunger to polish rod.

10 One of the common types of suspension devices comprises an arcuate saddle mounted on top the beam (the axis of the saddle are being substantially parallel to the longitudinal axis of the beam) and a cable trained over 15 the saddle and fastened to a clamp or grip on the polish rod. Due to the variable angularity of the walking beam during its oscillation, the cable has a tendency to bend comparatively sharply at its points of departure 20 from the saddle and is often cut by the flanges which define the saddle groove at said points of departure. Furthermore, there is a decided tendency to bend the polish rod to and fro due to the horizontal movement 25 of the saddle as the beam swings about its center.

The above mentioned characteristics are 30 obviously detrimental, and it is therefore the general object of my invention to provide a suspension device having none of these 35 objectionable characteristics.

It is further an object to provide a simple, 40 effective device which may be installed and removed with minimum effort and expense; in fact, it is so constructed that no attachment tools are needed for positioning the beam carried portion of the device, the bail by which the device is elevated and lowered by usual hoisting tackle being adapted to be 45 utilized for positioning purposes.

A better understanding of the invention 50 will be had from the following detailed description wherein other features of novelty and objects will be set forth. Reference will 55 be made to the accompanying drawings, in which:

Fig. 1 shows my device applied to a walking beam or pump jack, and in connection with a conventionally illustrated pump;

50 Fig. 2 is a fragmentary plan view of the free end of a walking beam with the beam carried portion of my device supported thereon; and

Fig. 3 is a section on line 3—3 of Fig. 2.

55 In Fig. 1 a usual walking beam or pump

jack is illustrated at 10, the beam being adapted to be oscillated by any well known crank means or the like (not shown). Numeral 11 designates a usual polish rod which extends above pump tubing 12 and is connected to a usual pump plunger (not shown) by a line of sucker rods (not shown).

My invention, broadly considered, comprises an equalizing device 13 for suspending the polish rod and its load from the walking beam 10, the device comprising a sheave 14 rotatably mounted on the walking beam, a usual grip or clamp 15 removably attached to rod 11, and a cable 16 trained over the sheave and attached to clamp 15 at opposite 65 sides of rod 11. It will be evident from consideration of the drawings that during oscillation of beam 10, cable 16 is free to revolve sheave 14, and that the cable may thus adjust itself as the angularity of the walking beam varies. This has the effect of equalizing the strain on opposite sides of clamp 15 so there is practically no tendency to bend the polish rod to and fro during beam oscillation. Furthermore, there is no possibility 70 of the cable being drawn around sharp corners or being bent back and forth. Therefore, it is assured that the useful life of the cable will be much longer than that of a cable drawn about a stationary, arcuate saddle.

The above description applies to the invention considered in its broader aspects, and it lies within the scope of my invention as broadly claimed along these lines to construct the sheave and its mounting in various manner. However, I will now describe the construction of a preferred embodiment of the invention, this construction having various advantages, certain of the advantages being discussed as the description progresses and other advantages being of a self-evident nature.

The beam carried portion of my device as illustrated comprises sheave 14, bail 18 having eyes 19, and shaft 20. Bail 18 is positioned so it straddles the sheave and so its eyes 19 are in register with the hub bore 21 of sheave 14. In assembling the device, shaft 20 is thrust through the bail eyes and hub bore, the bail being free to swing about the shaft while sheave 14 is held against longitudinal and rotary movement with respect to the shaft either by virtue of a force fit between the shaft and sheave hub or by 100 105 110

any of the well known keying or set screw means (not shown).

The shaft is adapted to extend transversely across the vertically extending beam 5 slot 22, which opens to the free end of the beam. Such a slot is customarily provided in every walking beam so I do not have to especially prepare a given beam for the installation of my device.

10 Sheave 14 extends downwardly into slot 22 and the bail eyes 19 are so gaged that they are adapted to contact with the opposite defining walls 23 of the slot to limit movement of the shaft and sheave transversely 15 of the beam.

The ends 24 or shafts 20 extend sufficiently beyond eyes 19 to insure sufficient bearing surface on top the beam, and loop 25 of bail 18 is adapted to be swung over the upstanding projection 26 (say, a bolt or lag screw) on the beam to limit movement of the shaft and sheave toward the open end 20 of slot 22.

When it is desired to "pick up" the polish 25 and sucker rods, bail 18 is swung to vertical position (see dotted lines in Fig. 1) and hoisting hook 27 may be attached directly thereto, connection being thus made between the suspension device and the usual hoisting 30 tackle (not shown) in the derrick. Bail 18 thus serves the dual purpose of a handling element and a positioning element.

It is believed a full understanding of the invention will be had from the foregoing, 35 but I wish it to be understood the invention, in its broader aspects, is not limited to the structure shown and described except for such limitations as may occur in the broader claims appended hereto.

40 Having described a preferred form of my invention, I claim:

1. In a device for suspending a pump rod from a walking beam, a horizontal shaft 45 removably supported on the beam, a sheave on the shaft, and a bail on the shaft, said bail being adapted to engage the beam in a manner to hold the sheave against horizontal displacement with respect to the beam.

2. In a device for suspending a pump rod

from a walking beam, a shaft, a sheave fixed 50 against movement longitudinally along the shaft, and a bail straddling the sheave and having terminal eyes fitted over the shaft at opposite sides of the sheave, the ends of said shaft extending an appreciable distance beyond said bail eyes and being adapted to have bearing on the beam.

3. In a device for suspending a pump rod from a walking beam which has a vertical slot extending therethrough, and opening to 60 the end of the beam, a horizontal shaft bearing on top the beam and extending transversely thereof across the slot, a sheave fixed against movement longitudinally along the shaft and extending downwardly into the 65 beam slot, a bail straddling the sheave and having terminal eyes fitted over the shaft at opposite sides of the sheave, said eyes being adapted to extend into the beam slot and engage opposite sides thereof to limit movement of the shaft transversely of the beam, and means for limiting movement of the shaft longitudinally along the beam towards 70 the open end of the slot.

4. In a device for suspending a pump rod from a walking beam which has a vertical slot extending therethrough, and opening to the end of the beam, a horizontal shaft bearing on top the beam and extending transversely thereof across the slot, a sheave fixed 75 against movement longitudinally along the shaft and extending downwardly into the beam slot, a bail straddling the sheave and having terminal eyes fitted over the shaft at opposite sides of the sheave, said eyes being 80 adapted to extend into the beam slot and engage opposite sides thereof to limit movement of the shaft transversely of the beam, the loop of the bail being adapted to embrace 85 an upstanding projection on top the beam for limiting movement of the shaft longitudinally along the beam towards the open end 90 of the slot.

In witness that I claim the foregoing I have hereunto subscribed my name this 20th 95 day of Nov., 1924.

EDWARD E. STEVENSON.
